MacNeil IP LLC, Cargo Organizer, Design U.S. Appl. No. 29/471,508, filed with the U.S. Patent and Trademark Office on on Nov. 1, 2013.

* cited by examiner

Primary Examiner — Katrina A Betton(74) *Attorney, Agent, or Firm* — Perkins IP Law Group LLC; Jefferson Perkins(57) **CLAIM**

The ornamental design for a cargo organizer, as shown and described.

DESCRIPTION

FIG. 1 is a perspective view of my design;
FIG. 2 is a second perspective view of the design shown in FIG. 1;

FIG. 3 is a plan view of the design shown in FIG. 1; and,
FIG. 4 is a bottom perspective view thereof.
The broken lines in FIG. 4 illustrate the portions of the cargo organizer that form no part of the claimed design.
